DESIGN FOR A HANDBAG OR SIMILAR ARTICLE

Harry Morris, Chicago, Ill.

Application April 15, 1947, Serial No. 138,399

Term of patent 14 years

(Cl. D87—3)

To all whom it may concern:

Be it known that I, Harry Morris, a citizen of the United States, residing in Chicago, in the county of Cook and State of Illinois, have invented a new, original, and ornamental Design for a Handbag or Similar Article, of which the following is a specification, reference being had to the accompanying drawing, forming part thereof.

Fig. 1 is a front perspective view of a handbag or similar article showing my design, with handles partially omitted for convenience of illustration.

Fig. 2 is the view of the opposite side thereof, with handles partially omitted.

Fig. 3 is a perspective view of the handbag or similar article illustrating the bottom and front view thereof, on a reduced scale, and

Fig. 4 is a top view thereof in opened position, with handles partially omitted for convenience of illustration.

The essential features of my design reside in the portions shown in full lines.

I claim:

The ornamental design for a handbag or similar article, substantially as shown and described.

HARRY MORRIS.
